UNITED STATES PATENT OFFICE

149,859

DESIGN FOR A DECORATIVE PAPER

William Burton, River Forest, Ill., assignor to United Wallpaper, Inc., Chicago, Ill., a corporation of Delaware

Application December 4, 1946, Serial No. 135,264

Term of patent 3½ years

(Cl. D59—10)

To all whom it may concern:

Be it known that I, William Burton, a citizen of the United States, residing at River Forest, in the county of Cook and State of Illinois, have invented a new, original, and ornamental Design for a Decorative Paper, of which the following is a specification, reference being had to the accompanying drawing, forming a part thereof.

In the drawing the figure is a plan view of a decorative paper showing my new design.

A design unit is outlined by broken lines. Said unit is repeated horizontally on the drawing as indicated by the extensions beyond the unit boundaries.

I claim:

The ornamental design for a decorative paper, substantially as shown and described.

WILLIAM BURTON.
